Inventor:
Anthony Norman Gerard Fokker,
By - B. Amper, Atty.

UNITED STATES PATENT OFFICE.

ANTHONY HERMAN GERARD FOKKER, OF AMSTERDAM, NETHERLANDS,

SAFETY TRIGGER GUARD ON MACHINE GUNS.

1,426,850.

Specification of Letters Patent. Patented Aug. 22, 1922.

Application filed September 1, 1920. Serial No. 407,538.

To all whom it may concern:

Be it known that I, ANTHONY HERMAN GERARD FOKKER, a subject of the Queen of the Netherlands, residing at Amsterdam, 5 Netherlands, have invented certain new and useful Improvements in Safety Trigger Guards on Machine Guns (for which I have filed application in Germany, #308,598, filed May 19, 1918), of which the following 10 is a specification.

The type of machine gun in which the breech block, the movement of which places a cartridge in position and operates the firing pin, is given a reciprocating movement 15 by mechanical means, such as a rotating crank, instead of being returned to the cocked position by the recoil of the explosion in the gun is well known. According to my copending application for Letters Patent of 20 the United States, Serial No. 407,540, filed September 1, 1920, the breech block is locked in position by means of locking levers pivotally mounted upon the frame of the gun and actuated by the operating crank 25 in such a manner as to engage with the breech block when the latter has reached its forward position in order to keep same in place while the shot is fired.

The object of the present invention is to 30 provide a catch for pulling the trigger and firing the gun which cannot reach the trigger until the locking levers are completely in place and lock the breech block. In addition the said catch is provided with a fine 35 screw adjustment so as to enable accurate timing of the moment of firing in relation to the position of the locking levers and it is further adapted to be swung outwards through a slot in the side of the gun frame, 40 thus locking the entire mechanism, and preventing the gun from being fired.

The accompanying drawings illustrate the parts of the gun mechanism relating to this invention.

45 In said drawings:—

Figs. 1 and 2 are horizontal and vertical longitudinal sections respectively.

Fig. 3 is a half horizontal cross section showing the operation of the trigger in de- 50 tail.

Figs. 4 and 5 are cross sections showing the positions of the breech block and the trigger catch, respectively.

The function of the various parts is as 55 follows: The operating crank *a*, which is given a continuous and uniform rotation, im-

parts a reciprocating motion to the breech block by means of a connecting rod as described in my copending application for Letters Patent of the United States, Serial 60 No. 407,539. It also carries the cam faced grooves *d* which cause the locking levers *c* and *c'* to pivot and lock the breech block *b* when it has reached the forward position, in the manner described in my patent application hereinbefore referred to, Serial No. 407,540. One of the locking levers *c* is provided with a pin *e* which engages with an oblique groove in the trigger catch carrier *g*. When the locking levers are pivoted into 65 the locking position as shown by the dotted lines in Fig. 3, the movement of the pin in the oblique slot causes the trigger catch carrier *g* to move backwards into contact with the trigger lever *i*, thus firing the gun. In 70 this manner the trigger catch cannot come into contact with the trigger lever until the locking levers are in place and the breech securely locked. The trigger catch *k* is provided with an adjusting screw *h* which 75 forms the point of contact with the trigger lever *i*. By adjusting the projection of this screw from the trigger catch a very fine adjustment of the exact moment of firing is obtained.

Further the trigger catch *k* is hingedly mounted on the trigger catch carrier *g* so that it may be swung out through a slot in the side wall of the frame of the gun, which limits its movement and prevents contact 90 with the trigger lever *i* and consequently makes it impossible for the gun to be fired.

Having now particularly described and ascertained the nature of my said invention and in what manner the same is to be performed, I declare that what I claim is:—

1. In a breech block mechanism for machine guns, operated by a rotating crank, and provided with pivoting levers which lock the breech block in position at the time 100 of firing, a sliding trigger catch actuated by one of the locking levers in such a manner as to prevent contact with the trigger while the breech block is unlocked.

2. In a breech block mechanism for machine guns, operated by a rotating crank, and provided with pivoting levers which lock the breech block in position at the time of firing, a sliding trigger catch actuated by one of the locking levers in such a manner as 105 to prevent contact with the trigger while the breech block is unlocked, said catch be-

ing provided with an adjusting screw which forms the point of contact with the trigger and the engagement of which with the trigger fires the gun.

- 5 3. In a breech block mechanism for machine guns, operated by a rotating crank, and provided with pivoting levers which lock the breech block in position at the time of firing, a sliding trigger catch actuated by
10 one of the locking levers in such a manner as to prevent contact with the trigger while the breech block is unlocked, and a sliding

carrier on which said trigger catch is hingedly mounted and said catch enabling it to be swung outwards through an aperture preventing its movement, thereby locking the entire mechanism and preventing the gun from being fired. 15

In testimony whereof I affix my signature in presence of two witnesses.

ANTHONY HERMAN GERARD FOKKER.
